(57) **CLAIM**

We claim the ornamental design for a wall panel, as shown and described.

DESCRIPTION

FIG. 1 is a perspective view of a wall panel.

FIG. 2 is a front elevation view of the wall panel of FIG. 1. FIG. 3 is a rear elevation view of the wall panel of FIG. 1 with mounting brackets shown in dashed lines.

FIG. 4 is a rear elevation view of the wall panel of FIG. 1 shown without mounting brackets

FIG. 5 is a right elevation view of the wall panel of FIG. 1.

FIG. 6 is a left elevation view of the wall panel of FIG. 1.

FIG. 7 is a left elevation view of the wall panel of FIG. 1 shown without the floating panel.

FIG. 8 is a top plan view of the wall panel of FIG. 1; and, FIG. 9 is a bottom plan view of the wall panel of FIG. 1. The broken lines are included for illustrative purposes only and form no part of the claimed design.
